Specification for Design.

Patented May 1, 1917.

Application filed February 24, 1917. Serial No. 150,823. Term of patent 7 years.

To all whom it may concern:

Be it known that I, ROBERT T. PARISEN, a citizen of the United States, and residing at Pittsburgh, in the county of Allegheny and State of Pennsylvania, have invented a certain new, original, and ornamental Design for a Top for Gas-Stove, of which the following is a specification, reference being had to the accompanying drawings, forming a part thereof and which illustrate my new design, wherein—

Figure 1 is a view in top plan of the stove

top. Fig. 2 illustrates the top partly in side elevation and partly in section, the portion in section being taken on line 2—2 of Fig. 1. Fig. 3 is an end elevation of the top.

I claim:

The ornamental design for a top for gas stove, substantially as shown.

ROBERT T. PARISEN.
